HARMAN A. TREMPER, OF HAMMONTON, NEW JERSEY.

Letters Patent No. 72,569, dated December 24, 1867.

IMPROVEMENT IN COPY-HOLDEES.

The Schedule referred to in these Letters Patent and making part of the same.

TO ALL WHOM IT MAY CONCERN:

Be it known that I, HARMAN A. TREMPER, of Hammonton, in the county of Atlantic, and State of New Jersey, have invented a new and improved Copy-Holder; and that the following description, taken in connection with the accompanying drawings, hereinafter referred to, forms a full and exact specification of the same.

Figure 1 is a front view of my invention.

Figure 2, a transverse vertical section of the same, taken in the line $z z$, fig. 1.

Figure 3, a transverse section of one of the rollers pertaining to the same, taken in the line $y y$, fig. 1.

Figure 4, a longitudinal section of one of the rollers pertaining to the same, taken in the line $z z$, fig. 1.

Similar letters of reference indicate like parts.

This invention relates to a copy-holder, intended for the use of compositors, and also for the use of proof-readers, book-keepers, lawyers, and copyists, by substituting a change of support, so as to allow of its being used on a table or desk.

A A represent the two rollers, on which the copy, shown in red, is wound. B B, the bars by which the copy is held or fastened to the rollers, which bars are slightly bent, so as to spring out when the openings in the movable ferrules D D are brought over them, and which bars are mortised into the rollers, so as to present a smooth surface. C C, fixed ferrules, by which the left-hand end of the bars is secured to the rollers. D D, movable ferrules, made with small spurs or projections, to catch the finger or thumb upon for the purpose of moving them, and openings the width of the bars, which allow the bars to spring out when the openings are brought over them. E E, thumb-wheels, by which the rollers are turned, fitted on the squared projections of the journals F F, and kept from slipping off by pins, by which arrangement the thumb-pieces may be removed when it is desired to take the copy-holder apart. G, a guide, made of spring-steel wire, bent so as to press lightly on the upper roller, and held in place by the slotted spurs or projections H H, which slits enable the ends of the wire to be slipped out when it is desired to remove the guide, said guide answering the double purpose of guide to the eye and of guiding the copy on to the upper roller when a short scrap is used, which will not extend to the lower roller. I and J, the end pieces, which support the rollers, the piece I being fastened to the rod L, and the piece J movable, by which arrangement the motion of the rollers may be retarded or entirely arrested by pressing said piece J against the ends of the rollers by means of the screw and thumb-nut K. L, a rod, passing through the pipe or socket M, and supporting the pieces I and J, enabling the copy-holder to be moved to the right or left, or vertically to any desirable angle, without unfastening it from the case. M, pipe or socket, which supports the rod L, and through which said rod is moved. N, screw by which the copy-holder can be made immovable in the pipe or socket M. O, a rod, with a curve of about forty-five degrees, which supports the copy-holder. P, a clamp, which, with the thumb-screw Q, fastens the copy-holder to the case. R, a desk or table-stand, made to fit on to the rod L in place of the standard designed for the case, when it is desired to use the copy-holder on a desk or table.

Directions for use: The copy-holder is first secured (the thumb-pieces toward the right hand) to the centre-bar of the upper case, (or to either of the end bars if desired,) by means of the clamp P and the thumb-screw Q. The copy-holder is then adjusted in a proper position, both horizontally and vertically, (which the rod L and socket M enable the compositor to do,) and firmly secured in such position by means of the screw N. The upper roller is then placed with the bar above and clear of the guide, the lower roller with the bar directly to the front. The rollers are then made immovable by means of the screw and thumb-nut K. The movable ferrule D of the upper roller is then turned till the bar springs out, the upper end of the copy is inserted under the bar, and the bar secured in its place. The lower end of the copy is then slipped under the guide as far as the lower roller, and secured to it in the same manner as to the upper roller, and wound on to the lower roller. The copy is then ready for use.

If desired, a number of sheets may be placed on the rollers at the same time by pinning the ends together. When it is desired to use the copy-holder upon a desk or table, remove the guide and the thumb-nut K, when the movable piece J, with the rollers, can be removed; then slip off the standard intended for use on the case, and substitute the desk-stand in its place.

Advantages of the copy-holder: First, it gives free access to all the boxes of the case without disturbing

the copy; second, the compositor or copyist is less liable to omit or double portions of the copy; third, it can be adjusted in a position to suit any eye, and for this reason is peculiarly adapted to persons of defective vision; fourth, the copy is secured in a small compass; fifth, it cannot be disturbed by wind or disarranged from any other cause.

Having thus described my invention, I claim as new, and desire to secure by Letters Patent—

1. The use of two rollers, A A, and the arrangement for securing the copy to them, consisting of the bars B B, the ferrules C C, and the movable ferrules D D, all combined and arranged substantially as described, and for the purposes set forth.

2. I claim the spring-guide G, with the slotted projections H H, substantially as described, and for the purposes set forth.

3. I claim the method of arresting the motion of the rollers by means of the movable end piece or roller-support J, and the screw and thumb-nut K, substantially as described, and for the purpose set forth.

4. I claim providing the rod L with both a clamp-arm or rod, O, and a stand, R, for the purpose of supporting the copy-holder under different conditions, as set forth.

HARMAN A. TREMPER.
